CASH REGISTER

Stephen P. Midouhas, Bristol, Pa., assignor to
 Kemline Metal Products Company, Bristol, Pa.,
 a corporation of Pennsylvania

Application February 4, 1948, Serial No. 6,262

2 Claims. (Cl. 235—25)

1

This invention relates to cash registers, and relates more particularly to a novel register of inexpensive construction which may be adapted for use as a toy, although it may also be embodied in a commercial machine of simple construction.

An important object of the invention is to provide a novel cash register having plural keys for registering varying amounts, say from five cents to one dollar, and wherein designating plates, one for each key, are arranged to be raised when the keys are depressed. Thus, each key and its associated plate have similar monetary units imprinted thereon, and when the designating plate is raised, the monetary unit becomes visible.

Another object of the invention is to provide novel means for retaining the plate in its elevated position while providing for its instant release when another key is depressed and its plate raised. Such means include the provision of vertically-spaced, elongated openings in the plate and a finger for each plate, the several fingers being carried by a pivoted bail. When a key is in its lowered position, the finger is disposed in the uppermost opening, and as the plate is raised when a key is depressed, the pivoted bail is arranged to rotate sufficiently to cause the finger to retract from the opening and then to enter the lower opening to support the plate in raised position before it falls due to gravity.

A further object of the invention is to provide improved means for rotating the bail comprising another pivoted bail arranged to be raised when a key is depressed, the two bails having interconnecting driving means therebetween.

A still further object of the invention is to provide improved means for releasing the cash drawer for outward movement when a key is depressed, the arrangement further providing means for ringing a bell.

In the drawings:

Fig. 1 is a plan view of a cash register embodying the present invention.

Fig. 2 is a horizontal section, the section being taken on line 2—2 of Fig. 4.

Fig. 3 is a broken vertical section taken on line 3—3 of Fig. 4.

Fig. 4 is a vertical section taken at right angles to the section of Fig. 3, the section being taken substantially through the center of the register.

Fig. 5 is a section similar to Fig. 4, but shows the relation of the parts when the drawer is in extended position.

Fig. 6 is a horizontal section taken on line 6—6 of Fig. 4.

2

The register of the present invention is provided with a housing which may be formed from sheet metal and includes a base wall 10, a rear wall 11, and an upper curved wall 12 whose front section 13 is formed with an opening 14 through which the designation plates may be seen. If desired, this opening may be provided with a suitable transparent window (not shown). Continuing forwardly, there is a curved section 15 and a horizontal front wall or shelf 16. The foregoing sections may, if desired, be formed from one continuous blank. Finally, the housing includes end walls 17 and 18. At its forward end, the housing is formed with an opening 19 to receive a cash drawer 23 which is provided with a front wall 24 and partitions 25 forming plural money compartments. It is formed with end walls 26 and 27, the lower edges of which slide on base wall 10 when the drawer is opened.

Means for moving the drawer outwardly to expose the compartments comprise an elongated, coiled tension spring 30 which is secured at its terminals in openings 31 in side walls 26 and 27. When the drawer is closed, the spring engages the forward faces of spaced angle brackets 32 and 33 secured on the upper surface of base wall 10, and the spring is under tension. The drawer is normally held in closed position within the housing, and when it is released for movement, as hereinafter described, it springs outwardly due to the action of spring 30. In its outward travel a depending finger 34 having a rear, inclined edge 35, which is carried on the lower surface of the drawer at its rear edge, contacts a lever 36 hinged at 37 on the base wall. A spring 40 is connected to the opposite end of the lever, the spring being secured to the base wall at 41. Thus, the free end of the lever is moved forwardly under spring tension, and when finger 34 releases the lever, it moves rearwardly with a rapid stroke and strikes a bell 42 mounted on the base wall. Outward movement of the drawer is limited by finger 34 which contacts an angle bracket 44 carried on the base wall adjacent its forward edge. When the drawer is manually closed, inclined edge 35 of finger 34 cams lever 36 slightly downwardly in order to pass rearwardly of such lever.

The mechanism includes plural keys 45 and 46 which are identical in construction, except that the forward edges of keys 45 are disposed on a lower plane than the forward edges of keys 46. The keys pass through elongated, vertical slots 47 in curved wall 15. Each of the keys has a finger-piece 50, and on the upper surfaces thereof are printed the numerical designations, as shown at

51, for the amounts deposited in the register. One key includes the legend, "No sale."

A substantially U-shaped frame having a front wall 52 and base wall 53, and a rear wall 54 of lesser height than the front wall, has inwardly-turned terminal flanges 55 which are secured in fixed relation on end walls 17 and 18 of the housing. Front wall 52 of the frame has a plurality of spaced, relatively deep slots 56 extending downwardly from its upper edge. These slots are of substantially the same width as the thickness of keys 45 and 46, and the lower edge of each slot forms a fulcrum for the key which is formed with an inverted V-shaped notch 69.

A second, generally U-shaped frame member has an upper wall 61 extending the full width of upper housing section 12. It further includes a vertical section 62 which is secured at 63 to the rear wall 11 of the housing, and a lower wall 64 of lesser width than its upper wall. These walls are provided with plural sets of aligned, rectangular openings 65 which receive and support designating plates 66 and 67 which are arranged in two rows, front and rear, respectively. On each of these plates is imprinted a number, shown at 71, which corresponds with the number on the key which has been depressed, and which actuates the plate. Each plate is provided with a short slot 72 at its lower end, a short, intermediate, elongated opening 73, and an upper, somewhat longer opening 74.

The rear terminal 75 of each lower key 45 normally rests on the upper edge of frame 54 and supports a front designating plate 66, such terminal being received in slot 72. Similarly, the rear terminal 76 of each upper key 46 supports a rear designating plate 67 and is received in the slot 72 at its lower end. It will be seen from this arrangement that when a key is depressed, it raises a designating plate from lowered position, wherein its number 71 is not visible, to an upper position where it is.

A generally horizontal bail 80 is formed with ears 81 at its opposite ends which are pivotally mounted at 82 on the end walls of the housing. A spring 83 urges the bail downwardly, and a rib 84 extending longitudinally of the bail rests upon the upper edges of keys 45 and 46, normally urging them downwardly to the rear of the fulcrum. An angular lever 85 forming a drawer latch is provided with a hook portion 86 which overlies the rear edge of bail 80. At its opposite end it is fulcrumed at 87 in frame 52. At its elbow it is formed with a finger 88 which passes through an opening 92 in frame 53, and when in lowered position it engages a bracket 89 rigidly supported at the rear of drawer 23 and holds the drawer in closed position. When the lever is raised, however, it releases the drawer for forward travel.

The bail 80 further carries on its upper surface an angular bracket having a base 93 and a hook portion 94. A second bail 95 has inturned ear portions 96 which are pivotally mounted on a shaft 97 mounted at opposite ends thereof in frame extension 98 which may be formed integrally with frame 62. Bail 95 is formed with a front extension 101 having a generally centrally disposed, laterally extending lug 102 which overlies and which is engaged by an upwardly extending projection 94 on bail 80 forming a cam surface. Bail 95 is further provided with spaced, relatively short, rearwardly-extending fingers 100, and with alternately disposed, somewhat longer fingers 103. The rear terminals of fingers 100 and 103 normally lie to the rear of front and rear

designating plates 66 and 67, respectively. Thus, when all the plates are down, the fingers reside in longer slots 74 in such plates. A torsion spring 104 carried at each end of longitudinal shaft 97 urges bail 95 in a clockwise direction, when viewed as in Fig. 4, and accordingly urges fingers 100 and 103 carried thereby rearwardly.

When a plate is in raised position it is supported in such position by a finger 100 or 103 which has entered the lower slot 73. When in lowered position, the finger enters upper slot 74 which has no function except to provide a clear space for the finger to enter.

The operation of the register is as follows. The parts are normally in the position shown in Fig. 4. The front sections of all keys are in raised position, and the rear sections are held in lowered position due to the action of spring 83 urging bail 80 downwardly. Now one of the lower keys 45 is depressed, as shown in Fig. 5. This raises one of the front designating plates 66. This movement raises bail 80 against the tension of spring 83 which raises the free end of lever 85, thus releasing the cash drawer for outward travel. Cam element 96 carried by bail 80, and which underlies lateral lug 102 on bail 95, acts to rotate the latter in a counterclockwise position when viewed as in Fig. 5 against the tension of springs 104. This movement draws fingers 100 and 103 carried by bail 95 forwardly, which frees the fingers from the longer slots 74 in the plates, thus permitting upward travel of the plates. This movement occurs simultaneously with the raising of the designating plate.

Since elements 84 and 102 are journaled on different axes, they travel in different arcuate paths, and when bail 95 has thus been rotated slightly, lug 102 is freed from engagement with cam element 96 and bail 95 and its fingers spring back to starting position, which occurs before the raised plate can fall, due to gravity and to the release of the depressed key. This action causes one of the fingers to enter the shorter, intermediate slot 73 in the raised plate, thus holding the plate in raised position until the next key is depressed. Upon the release of the key, lug 102 on bail 95 has already returned to starting position, and lug 94 on bail 80 moves to its initial position under the other cam element.

Single keys may be depressed or plural keys, and in case of the latter, plural designating plates are raised and retained in such position.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What I claim is:

1. In a cash register, the combination of a housing, plural operating keys extending from the housing, a fixed frame member providing substantially centrally disposed fulcrums for the keys, plural designating plates mounted for vertical sliding movement and having vertically spaced slots and contacting the rear terminal of the keys and arranged to be raised thereby when the forward ends of the keys are depressed, a pivoted bail overlying the keys to the rear of the fulcrums

and arranged to be raised by such keys, a second bail pivotally mounted at its upper end and arranged to swing forwardly and provided with rearwardly extending fingers, each of which is normally disposed in the upper slot in one plate when the latter is in lowered position and in the lower slot when the plate is in upper position to support such plate, a spring which urges the second bail rearwardly, an upwardly projecting cam element carried by the first bail and a laterally extending lug carried by the second bail and which normally overlies the cam element and is moved thereby to swing the second bail forwardly to disengage the fingers from the slots during travel of the plates.

2. In a cash register, the combination of a frame, plural operating keys provided with numerical indicia at their forward ends, a fixed frame member providing fulcrums for the keys intermediate their ends, a designating plate for each key and having vertically spaced slots and contacting the rear terminal of such key and arranged to be raised thereby when the forward end of the key is depressed, each plate being provided at its upper end with numerical indicium corresponding to that on the key which it contacts, a generally horizontal bail pivotally mounted on the frame adjacent the axis of the key fulcrum and positioned so as to overlie the keys to the rear of the fulcrums so as to be raised by such

keys, a second pivoted bail provided with rearwardly extending fingers, each of which is disposed in the upper slot in one plate when the latter is in lowered position and in the lower slot when the plate is in upper position to support such plate, a spring for urging the second bail rearwardly, means for withdrawing the fingers from the slots to allow for travel of the plate, such means comprising a laterally projecting lug carried adjacent the lower edge of the second bail and an upwardly extending cam element carried by the first bail which normally underlies the lug and which is arranged to cam the lug, and the bail upon which it is supported, rearwardly when the cam element moves generally upwardly upon the depressing of a key, the cam element releasing the lug for rearward travel after limited forward travel to allow the fingers to re-enter the slots in the plates.
